UNITED STATES PATENT OFFICE.

DORSEY F. ASBURY, OF WASHINGTON, DISTRICT OF COLUMBIA.

VALVE-OPERATING MECHANISM.

Application filed April 19, 1920. Serial No. 374,997.

REISSUED

To all whom it may concern:

Be it known that I, DORSEY F. ASBURY, a citizen of the United States, residing at Washington, in the District of Columbia, 5 have invented certain new and useful Improvements in Valve-Operating Mechanisms, of which the following is a specification.

My invention relates to valve operating mechanisms and has for its purpose to provide improvements in the construction of such mechanisms, particularly of the "rocker arm" type, whereby noise, friction, lubrication and the necessity for adjustment of 15 parts is eliminated.

In my former application for like improvements, filed Feb. 21, 1920 and serially numbered 360,487, I disclosed an arrangement embodying a spring arranged to both 20 yield and act positively as an element of the mechanism, while in my present invention I make use of a yieldable wedging arrangement to accomplish the purposes of the spring element of my former invention. 25

In the drawings—

Fig. 1 is a vertical section through an internal combustion engine showing the application of one form of my invention there- 30 to with the parts in an exaggerated normal position;

Fig. 2, a similar view showing the position of the parts when the valve is operated;

Fig. 3, a section on the line 3—3 of Fig. 2;

Fig. 4, a view similar to Fig. 1 of a modified form of my invention; and

Fig. 5, a view similar to Fig. 1 of another modified form of my invention.

Referring to the drawings in detail, particularly to Figs. 1, 2 and 3, A designates generally a portion of an internal combustion engine of the "valve-in-head" type and includes as is usual a cylinder 10, piston 11 and cylinder head 12. Seating on the head 12 is a puppet valve 13 including a stem 14 which extends through and projects above the head 12 and has associated therewith a spring 15 holding the valve normally to its seat. Disposed in operative relation to the valve 13 is a tappet rod 16 and bridging the upper ends of said tappet rod and the valve stem is a rocker or lever arm 17. Tappet rod 16 is operated in any well known or preferred manner, as by means of a cam (not shown) to actuate the lever arm which

in turn is designed to impart desired movements to the valve.

As in my former application previously identified, I provide a rolling contact between the lever arm and the valve stem and between the lever arm and the tappet rod in order to eliminate friction and thereby avoid the necessity of lubricating these relatively contacting parts of the mechanism. 60 This is accomplished by providing convexed surfaces on the lever arm adapted to roll on the upper flat ends of the valve stem and tappet rod as the lever arm is rotated on its pivot during operation of the mechanism. 65

In order to provide a flexible fulcrum for the lever arm, whereby I am enabled to eliminate noise and friction during operation of the mechanism, I pivot the lower 75 end of a link 18 to a suitable bracket 19 secured to the head 12 and interposed between the link and an intermediate portion of the lever arm a floating member 20 having a rolling contact with both the link and the lever arm. Preferably the floating member 20 consists of a ball and in order to retain the same in place between the link and the lever arm I extend the link through a vertical slot 21 in the lever arm and seat 80 the ball in a depression formed by chamfering the inner upper edges of the side walls of said slot. These chamfered edges of the lever arm are curved in the longitudinal direction of the lever arm at a 85 greater radius than the radius of the ball and likewise the face of the link contacting with the ball is curved corresponding to the curvature of the ball contacting faces of the lever arm. Thus relative movement of 90

the link and lever arm in opposite directions obviously will produce a separation of these parts at right angles to the direction of said relative opposite movement due to the progressively increasing wedging effect produced between the ball and the curved faces of the link and lever arm. Connecting the link with the lever arm is a spring 22 which exerts a tension tending to move the link and lever arm in relative opposite directions 100 and as result normally maintains the ball in contact with the lever and link on the inclined surfaces and the lever in contact with the tappet rod and valve stem, respectively, the force of said spring intensified 105 by the wedging effect referred to reacting on the tappet rod 16 and valve stem 14 from

the cylinder head 12 through the bracket 19, link 18, ball 20 and lever arm 17.

In Figure 1 I have exaggerated the normal position of the ball with respect to the link and lever arm. When the mechanism is operated by an upward movement of the tappet rod to depress and open the valve the force of the spring 22 will be overcome due to the wedge connection between the link and the lever arm and the ball will roll to the position shown in Fig. 2 when it will act as a positive element of the mechanism, its initial action being a yieldable one as is apparent.

15 In Fig. 4 I show an arrangement having the same action as the arrangement just described, but embodied in a slightly different structure. In this latter instance I provide an L-shaped link 18' and pivot it at its elbow 20 to a bracket 19' secured to the cylinder head. Between the vertical arm of this link and the lever arm I provide a rolling wedging contact similar to that provided in the preferred form of my invention with the exception that I utilize a roller 20' in lieu of the ball 20. The spring 22' I interpose between the bracket 19' and the lateral extension of the link and this spring tends to rotate the link on its pivot and cause a 30 wedging action between the roller and lever arm to maintain the parts of the mechanism in contact.

In Fig. 5 of the drawings is illustrated one method of accomplishing the purposes 35 of my invention in mechanisms of the type where the actuator or tappet rod is aligned with the valve. In such instances I may interpose between the ends of the valve stem and tappet rod a member 23 and between 40 opposite faces of this member and the respective ends the valve stem and tappet rod interpose balls 20''. Curved surfaces may be provided on the member and on the ends of the valve stem and tappet rod to produce 45 a desired wedging effect and a spring 22'' of any desired type may be utilized to maintain the parts of an arrangement of this character in contact.

It will be obvious that various other arrangements may be provided for accomplishing the results gained by the present structures and that the present structures themselves may be modified in various respects as for instance by providing an anti-friction roller in lieu of the ball in the preferred form of the invention, or by providing a single curved wedging surface either on the link or on the lever arm instead of wedging surface on each and for such reasons I desire to have it understood that I reserve as my right all such variations as may be included within the scope of the appended claims.

I claim—

1. In a valve operating mechanism, a

valve, an actuator therefor, a lever arm between said valve and actuator, and a movable fulcrum for said lever arm including rollable wedging means to maintain said lever arm in contact with said valve and actuator. 70

2. In a valve operating mechanism, a valve, an actuator therefor, a lever arm between said valve and actuator, a movable fulcrum for said lever arm, and wedging 75 means acting between said movable fulcrum and said lever arm to maintain said lever arm in contact with said valve and actuator.

3. In a valve operating mechanism, including a pair of members one of which is provided with a wedge surface, and bodily movable means between said members having rollable contact with said wedge surface to maintain the parts of the mechanism in 85 contact.

4. In a valve operating mechanism, a valve, an actuator therefor, a lever between said valve and actuator, a pivoted link, a wedging connection between said link and said lever, and spring means associated with said link constantly exerting a force to cause said wedging connection to maintain the parts of the mechanism in contact. 90

5. In a valve operating mechanism, a valve, an actuator therefor, a rocker arm between said valve and actuator, a movable fulcrum for said rocker arm, a wedging surface on said rocker arm and a rollable member disposed between said rocker arm and 100 said movable fulcrum and engaging the wedging surface of the rocker arm to thereby constantly maintain the elements of the mechanism in contact.

6. In a valve operating mechanism for 105 engines, a valve, an actuator therefor, a rocker arm between said valve and actuator, a link supported by the engine and providing a movable fulcrum for said rocker arm, wedging surfaces on the link and rocker arm 110 respectively, a rollable member disposed between said link and rocker arm and engaging their respective wedging surfaces, and yieldable means constantly tending to relatively move said link and rocker arm to thereby cause said rollable member to react from said wedging surfaces and thereby maintain the parts of the mechanism in contact. 115

7. In a valve operating mechanism, a 120 valve, an actuator therefor, a lever arm between said valve and actuator, and a movable fulcrum for said lever arm including wedging means to maintain said lever arm in contact with said valve and actuator. 125

8. A valve operating mechanism including a pair of members one of which is movable and provided with a wedge surface, a bodily movable element between said members having rollable contact with said wedge 130

surface, and means acting to cause a wedging action between said wedge surface and said element, thereby to maintain the parts of the mechanism in contact.

6 9. A valve operating mechanism including a pair of movable members one of which is provided with a wedge surface, an element between said members having rollable contact with said wedging surface, each of said 10 members being movable independently of said rollable element, and means acting to cause a wedging action between said wedge surface and said rollable element, thereby to maintain the parts of the mechanism in 15 contact.

10 10. A valve operating mechanism including a pair of members one of which is movable, a wedge surface on each member, a bodily movable element between said members having rollable contact with the wedge surface of each member, and means acting 20

to cause a wedging action between said wedge surfaces and said element thereby to maintain the parts of the mechanism in contact.

25

11. A valve operating mechanism including a pair of movable members each of which is provided with a wedge surface, an element between said members having rollable contact with the wedge surface of both 30 members, each of said members being movable independently of said rollable element, and means acting to cause a wedging action between said wedging surfaces and said rollable element, thereby to maintain the parts 35 of mechanism in contact.

In testimony whereof I hereunto affix my signature in the presence of two witnesses.
